UNITED STATES PATENT OFFICE.

CHESTER T. RABERT, OF HUNTINGTON, WEST VIRGINIA.

SEAT OR HAT CHECK.

Application filed March 4, 1924. Serial No. 696,848.

This invention relates to a seat or hat check for use on passenger trains.

The object of the invention is to provide a seat or hat check of this character which is simple and entirely practical in its nature and which identifies the particular trip and time at which it is issued in such a manner as to preclude the possibility of its subsequent use.

10 Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view showing 20 one embodiment of the invention;

Figure 2 is a fragmentary perspective view, showing the coupon of the check as it usually appears when in the possession of the passenger;

25 Figure 3 is a plan view of the coupon; and Figure 4 is a similar view of the stub.

Referring to the drawings, and more particularly to Figure 1, it will be seen that the seat or hat checks constituting the present invention are preferably put up in the form of a book which is designated generally at 5. Any desired number may be provided in each book, and in the embodiment shown approximately twenty-five are 30 included although of course fifty, one hundred, or any desired number may be included.

The seat and hat checks are all of identical construction, and each includes a stub 6 and a coupon 7. Each stub 6 is fastened in the book and each coupon 7 is detachably connected to its stub by a perforated connection 8. Thus the coupons may be readily torn or detached from their stubs.

The coupons and stubs bear corresponding 45 identifying indicia which preferably take the form of corresponding serial numbers, designated at 9 and 10 on the stub and coupon respectively and disposed in spaces or panels provided on these elements. Of course it is to be understood that the coupon and stub of each check bears the same serial number. In Figure 1 several coupons have been torn off so that the serial number on the topmost stub is different from the serial number on the topmost coupon remaining 50 in the book.

The stub 6 is provided with panels 11 and 12, the panel 11 being above the serial number and containing indicia and spaces facilitating the endorsement on the stub of the 60 date, the train number, and the station numbers which indicate the conductor's trip. As shown in Figure 4 this indicia preferably consists of the word "Date" followed by a dotted line, the words "Trn. No." followed by a dotted line, the word "From" followed by a dotted line, and the word "To", these words being arranged one above the other and the words "From" and "To" being adjacent. The panel 12 is divided by 70 a line 12^a into two spaces, one of which is headed by the word "From" and the other of which is headed by the word "To". These spaces are designed to receive the station numbers which indicate the trip of the 75 passenger.

Each coupon 7 includes in addition to the serial number a centrally disposed panel defined by heavy black lines 13 and divided up by lighter lines into rectangular spaces 80 which contain columns of numbers 14 ranging from zero to nine. These columns are headed by the word "To" designated at 15. The lines 13 define with the marginal lines of the ticket a marginal space in which 85 letters designated at 16 are applied. Preferably the letters range from "A" to "Z".

Above the serial number of the coupon a blank space, designated at 17, is left and is designed to receive the number corresponding to the number of the station to which the passenger is travelling.

In use, the conductor enters in the spaces of the panel 11 of the stub the date, the train number, and the station number which 95 define his trip. These entries are however necessary only on the topmost stub of each book. When the conductor takes a ticket from a passenger, he punches from the columns of numbers 14, such numbers as designate the number of the station to which the passenger is travelling. If the station is located on a branch line of the railroad it will probably be designated by a number and a letter, and in such event the conductor 100 also punches the proper letter in the series of letters 16. The conductor also notes on the stub of the coupon so punched, the numbers corresponding to the stations between which the passenger is travelling. The conductor also writes in large bold letters and in the space 17 a number which corresponds 110

to the number of the station to which the passenger is travelling in order that the conductor may tell at a glance in passing through the passenger car the destination of the traveller for when the check is inserted in the hat band, as it usually is, and as shown in Figure 2, the number in the space 17 will be prominently displayed. The serial number is also prominently displayed 10 so that the conductor can tell at a glance whether he has a stub corresponding to the hat check. This prevents a passenger from making a second or unauthorized use of a hat check. This is an important advantage 15 when it is considered that hat checks as now constituted may, and sometimes are used to secure a passage on railway trains for persons who have not paid their fares for if a passenger retains a hat check issued to him 20 on one trip there is nothing in the nature of the hat check as now constituted effective to prevent him from using the same to secure a passage on the railway later without paying his fare.

25 With the present invention however the conductor of course knows the range of the serial numbers of the checks issued on each trip and therefore even if the hat checks are kept by the passengers they cannot be 30 used later.

At the end of each trip the stubs of the hat checks that have been issued during the trip are destroyed.

I claim:

35 1. A seat or hat check for use on passenger trains and including a stub for the conductor, and a coupon for the passenger, the stub and the coupon bearing corresponding identifying indicia, the stub having an appropriately designated space in which the destination of the passenger may be indicated, and the coupon having appropriately designated means thereon whereby the destination of the passenger may be indicated.

45 2. A seat or hat check for use on passenger trains and including a stub for the conductor and a coupon for the passenger, the stub and the coupon bearing corresponding serial numbers to identify the coupon with its stub, the stub having an appropriately designated space in which the destination of the passenger may be indicated, the coupon having columns of numbers and figures, the numbers and figures being adapted to

55 be selectively punched by the conductor to indicate the destination of the passenger.

3. A seat or hat check for use on passenger trains and including a stub for the conductor and a coupon for the passenger, the

stub and the coupon bearing corresponding 60 serial numbers to identify the coupon with its stub, the stub having an appropriately designated space in which the destination of the passenger may be indicated, the coupon having columns of numbers and figures, 65 the numbers and figures being adapted to be selectively punched by the conductor to indicate the destination of the passenger, the coupon having a blank space at the top wherein the destination of the passenger 70 may also be indicated by the conductor.

4. A seat or hat check for use on passenger trains and including a stub for the conductor and a coupon for the passenger, the stub and the coupon bearing corresponding 75 serial numbers to identify the coupon with its stub, the coupon having columns of numbers and figures, the numbers and figures being adapted to be selectively punched by the conductor to indicate the destination of 80 the passenger, the stub having appropriately designated spaces thereon whereby the conductor may indicate his trip, the train number and the trip of the passenger.

5. A seat or hat check for use on passenger 85 trains comprising a stub for the conductor and a coupon for the passenger, the coupon being adapted to be mounted in the seat or hat and being provided at the uppermost part thereof with a designated number-receiving space, said coupon and said stub bearing identifying indicia consisting of corresponding serial numbers, the serial number of the coupon being located in the number receiving space and being thus always exposed to view whereby the conductor may determine at a glance the validity of all seat or hat checks which he views.

6. A seat or hat check for use on passenger 100 trains comprising a stub for the conductor and a coupon for the passenger, the coupon being adapted to be mounted in the seat or hat and being provided at the uppermost part thereof with a designated number-receiving space, said coupon and said stub bearing identifying indicia consisting of corresponding serial numbers, the serial number of the coupon being located in the number receiving space and being thus always exposed to view whereby the conductor may determine at a glance the validity of all seat or hat checks which he views, said coupon also having a defined space above said number-receiving space adapted to receive an indication of the destination of the 110 passenger.

CHESTER T. RABERT.
